ELECTRICAL METER HAVING CALIBRATION MATRIX

Melvin E. Stanford, Saratoga County, and Albert J. Morford, Albany County, N.Y., assignors to Systomatication, Inc., Schenectady, N.Y.

Filed Mar. 15, 1968, Ser. No. 10,987

Term of patent 14 years

Int. Cl. D10—10

U.S. Cl. D26—1

Fig. I.

Fig. 2.

Fig. 3.

Fig. 4.

FIG. 1 is a perspective view of an electrical meter having calibration matrix designed in accordance with the invention;

FIG. 2 is a plan view of the electrical meter having calibration matrix shown in FIG. 1;

FIG. 3 is a side view of the electrical meter having calibration matrix; and

FIG. 4 is a back view of the electrical meter having calibration matrix according to the invention.

The characteristic features of the design reside in the particular arrangement and appearance of the calibration matrix together with the associated selectors on the forward portion of the meter.

We claim:

The ornamental design for an electrical meter having calibration matrix, as shown and described.
